ELECTRICAL ADAPTER UNIT

Thomas E. Carroll, New York, N.Y.

Application November 10, 1948, Serial No. 59,367

2 Claims. (Cl. 173—344)

1

This invention relates to an adaptor for enabling electric lamps and other electrical devices having Edison or screw-type bases to be used with outlets or receptacles of the bayonet or bi-post types.

In the larger sizes of incandescent lamps, as from 300 watts to 1500 watts, a type commonly referred to in the trade as a bi-post lamp, such as disclosed in Wright Patent No. 2,098,080, is extensively used in theatres, motion picture and other photographic studios, office buildings, gasoline filling stations and on docks and wharves along water fronts. Because of the considerable heat generated by these high wattage lamps when in operation, their contact terminals are in the form of two specially designed studs or posts such as shown in the aforesaid Wright patent. This terminal construction requires the use of specially designed bi-post sockets for receiving and mounting the lamps, which sockets are permanently mounted in the lighting systems and fixtures where the bi-post lamps are used.

In the Edison or screw-base lamp, as distinguished from the bi-post lamp, there is a large variety of different types, including low wattage lamps, commercially available for different purposes, such as lamps for general illumination purposes, photoflash and photoflood lamps, spot lights, enlargers, color lamps and others. It is, therefore, often desired to employ the screw-base type of lamps in systems or fixtures which are adapted to receive only the bi-post type of lamp or to replace the bi-post lamp with a screw-base lamp, and heretofore it has been necessary to have an electrician change out the bi-post sockets to effect this, which in most instances is an inconvenient, time-wasting and somewhat expensive procedure.

An object of the present invention is the provision of a suitable adaptor which enables a screw-base lamp of any desired wattage or type readily to be used with a bi-post socket without requiring removal or replacement of the socket, and which makes possible the use of bi-post and screw-base lamps interchangeably in lighting systems or fixtures equipped with bi-post sockets or receptacles.

Another object of the invention is an adaptor of the character described which contains relatively few parts, which is rugged in construction, and which is well adapted for quantity production methods and therefore may be sold at a low price.

Other objects and advantages will be apparent from the following detailed description of an

2

illustrative embodiment of the invention, taken in connection with the accompanying drawings in which:

Fig. 1 is a view, in elevation, of an adaptor constructed in accordance with the invention, showing its relationship to a bi-post socket and a screw-base type of incandescent lamp, the several units being shown disengaged from each other;

Fig. 2 is a view showing the bottom of the bi-post socket illustrated in Fig. 1;

Fig. 3 is a cross-section of the adaptor taken along the line 3—3 of Fig. 1; and

Fig. 4 is an exploded view of the terminal posts, insulating body piece and inner parts of the assembly comprising the adaptor.

Referring to the upper unit of Fig. 1 and to Fig. 2, the bi-post socket shown has a body piece 10 of porcelain or other suitable insulating material, the socket being rigidly secured to an outlet fixture by means of a conduit which comprises a bracket portion 11 and a sleeve 14 screwed to the end of a conduit 15. Conductors 16 in the conduit electrically connect the socket to the lighting circuit. The porcelain body 10 is secured, by means of two machine screws 13, between the bracket 11 and a metal clamping ring 12. A fibre washer 17 between the body 10 and bracket 11 minimizes danger of breakage of the porcelain.

Leaf members 20 of spring steel are each secured at one end thereof to the porcelain body 10 by means of a machine screw 21 which passes through the fixed end, and the spring members have bayonet slots 20a for receiving the terminals of a bi-post lamp. The terminal posts 34 of my adaptor unit, shown in the middle portion of Fig. 1, are therefore of this type. The reduced portions 34a of the adaptor posts enter the curved slots in the spring members 20 when the adaptor is inserted, and the adaptor is rotated through a small angle, in a clockwise direction as viewed in Fig. 2, in the same manner as that in which a bi-post lamp would be inserted. The shoulders formed by the reduced portions 34a of the adaptor terminal posts engage the edges of the curved bayonet slots 20a and flex the spring leaf members 20 slightly to provide firm engagement of the upper end of the base 30, Fig. 1, of the adaptor with the lower rim 12 of the bi-post socket, thereby to firmly secure or lock the adaptor in proper position in the socket.

Electrical contact between the adaptor and the bi-post socket is provided by sets of curved brass contact springs 22 in the socket, which contacts

are engaged by the adaptor posts 34 when the adaptor is inserted and rotated in the socket, as above described. Curved clamping members 23 of spring steel apply the proper resilient pressure to the contact springs 22. The sets of contact springs are connected by metal straps 24 and connecting screws 25 to the conductors 16, the straps 24 being secured to the body 10 of the bi-post socket by means of machine screws 26.

The adaptor unit of the invention, shown in the middle portion of Fig. 1 and in Figs. 3 and 4, comprises a body portion or base 30 of porcelain or other suitable insulating material with an inner brass screw shell or socket 31 for receiving the screw base of an electric lamp, attachment plug or other electrical device, such as the base 27 of an incandescent lamp 26 shown in the lower portion of Fig. 1. The socket 31 may be either of the Mogul size or the medium size, depending upon the size of the lamp to be used. Lamps of the 300 watt size and larger are usually provided with the larger Mogul screw bases, while lamps smaller than 300 watts usually have the conventional medium size bases. The upper end of the base 30 has two apertures 30a, Fig. 4, with seating portions 30b for engaging and mounting the shoulder portions 34b and for receiving the adjoining reduced portions 34c of the bi-post terminals 34. Preferably, although not necessarily, the length of each of the reduced portions 34c is such that when the terminals are inserted in the apertures 30a the ends of the reduced portions are flush with or only slightly above the inner surface of the body 30 so that the base 32 of the brass socket 31 may be tightly clamped to the body 30 by means of a machine screw 36 which is screw-threaded into one of the terminals 34, thereby also securing the terminal and the brass socket to the body. The other terminal 34 is similarly secured to the body by means of a machine screw 37 which passes through a centrally positioned brass contact spring 33 hereinafter described. The shoulder portions 34b of the terminals are firmly seated on the shoulders 30b of the body, and thus insure rigidity of the terminals. A close fit between the portions 34b and 34c of the terminals and the apertured portions 30a of the body is desirable to brace the terminals against lateral stresses when the adaptor is inserted in or removed from the bi-post socket.

The base 32 of the brass shell 31 is electrically connected to one of the terminals 34 by means of the machine screw 36, and the base has a rectangular cutout portion 32a as seen in Fig. 3 to provide clearance for the central brass contact spring 33 of the adaptor socket which is engaged by the center contact 28 of the lamp 26 of Fig. 1 when the lamp is screwed into the adaptor. The contact spring 33 is electrically connected by means of the machine screw 37 to the other terminal 34 of the unit. A machine screw 38, which passes through the base of the contact spring and into an aperture of the body 30, such as shown at 30c in Fig. 4, is tightened with a threaded nut to mechanically lock the spring in position to maintain suitable spacing between it and the base of the shell 31. Sealing wax or other suitable compound 39 seals the aperture above the nut on screw 38. Two other machine screws 40, Figure 3, pass through the base of the brass shell and into apertures in the body 30 and are tightened with threaded nuts to provide additional rigidity to the brass shell, the apertures above these nuts also being sealed with sealing wax.

The body 30 with the apertures 30a and 30c therein is so constructed that it may readily be molded in one piece, and this appreciably reduces the manufacturing costs. Also, the five machine screws 36, 37 and 40 may be of the same kind, size and length if desired, so that only one type of screw need be kept in stock for the assembly of the adaptor unit.

If the screw shell 31 in the adaptor is of the Mogul type and it is desired to insert either a lamp, an attachment plug of an extension cord or other device having a medium size screw base, a reducing plug which has an outer screw shell of Mogul size and an inner screw shell of medium size is commercially obtainable, and such a plug may be inserted in the adaptor unit whereby the devices with medium size screw bases may be used with bi-post sockets of the character described. This enables screw-base lamps of different sizes to be used interchangeably with bi-post lamps in a system or apparatus equipped only with bi-post sockets, so that these sockets may be used with a large line of standard lighting and power equipment. The arrangement is particularly advantageous in cases of an emergency where an extension cord or other wire extension is needed, and which otherwise could not be attached to the bi-post socket. The terminals 34 of the adaptor have rounded edges 34d adjacent to the reduced portions 34a which enter the curved slots 20a of the bi-post socket, in order to facilitate insertion and removal of the adaptor in the socket and to prevent binding.

The adaptor of the invention also has the advantage of extending a screw-base lamp a further distance from the bi-post socket of a device, which is highly desirable in the case of photo-flash or projection type lamps in which the filament of the lamp has to be located at the proper position with respect to the reflector and lens system of the lamp in order to substantially correspond to the position of the filament in a bi-post lamp for which the device was designed, thereby to obtain the correct illumination. This is because the screw-base type of projection lamp has a filament which ordinarily is closer to the lamp base than the filament of a bi-post lamp is to its base. The adaptor therefore is a great convenience to those using photographic flood light and projection equipment of the type which normally employs bi-post lamps, and gives the user of such equipment a wide range of screw-base lamps of which a large variety of different types and sizes are obtainable, thereby making the equipment available for a number of different purposes.

Various modifications of the adaptor unit will readily occur to those versed in the art without departing from the spirit or scope of the present invention which is, therefore, not to be regarded as limited except as indicated by the scope of the appended claims.

What is claimed is:

1. An adaptor unit for connecting a screw-base electrical device to a bi-post socket of the type having bayonet slots and contacts positioned beneath said slots, said adaptor unit comprising a preformed body member of insulating material having a closed end with two apertures extending through said closed end, terminal posts respectively having the inner ends thereof extending through and mounted in the apertures in said body member, the outer ends of said posts projecting from the closed end of said

body member and having reduced portions for entering the bayonet slots in the bi-post socket and other portions for electrically engaging the contacts in said socket when the terminal posts of the adaptor unit are inserted and rotated in the bayonet slots, the other end of said pre-formed insulating body member comprising a skirt portion surrounding a screw-shell socket assembly mounted therein for receiving a screw-base electrical device, the inner ends of the terminal posts each having a portion of larger diameter followed by a portion of smaller diameter and the apertures in the body portion in which the posts are received each having larger and smaller diametral portions respectively contiguous to said portions of the post received therein thereby to seat the post and brace the outer end thereof against lateral forces exerted thereon, and metal clamping members for clamping the posts and the socket assembly to each other and to intervening portions of the insulating body member which form said smaller

10

20

diametral portions of the apertures in which the posts are received.

2. An adaptor unit according to claim 1, in which said metal clamping members also electrically connect the screw-shell socket assembly members of opposite polarity respectively to the two terminal posts of the unit.
